UNITED STATES PATENT OFFICE.

JAMES A. ANDREWS AND JOHN W. HERBERT, OF BIDDEFORD, MAINE.

LOOM-CHECK MOUNTING.

Application filed October 6, 1924. Serial No. 741,890.

To all whom it may concern:

Be it known that we, JAMES A. ANDREWS and JOHN W. HERBERT, citizens of the United States, residing at Biddeford, in the county of York and State of Maine, have invented new and useful Improvements in Loom-Check Mountings, of which the following is a specification.

This invention relates to certain new and useful improvements in loom check mountings, and the primary object thereof is to provide an improved mounting for the check.

The general practice heretofore has been to cut a socket in the wood lay of the loom, and insert a nut therein for the bolt that secures the loom check to the lay, but with this construction the disadvantage prevails of the nut working loose in the wood and the splitting of the lay at each end.

The present invention therefore aims to overcome the objection supra and to provide a mounting which can be quickly applied to the loom lay which is of economical construction, and which cannot work loose in ordinary usage to which the loom is subjected, and will overcome the splitting of the lay at the ends.

The invention has still further and other objects which will be later set forth and manifested in the course of the following description.

In the drawings:

Figure 1 is a front elevation of the invention applied to a member of the loom frame, the latter shown in fragment.

Figure 2 is a section on line 2—2 of Figure 1 and

Figure 3 is a section on line 3—3 of Fig. 1.

In proceeding in accordance with the present invention a bracket is employed which has a vertical front web 1 formed to seat flat against the outer vertical face of the lay L of the loom. The lower side of the web 1 is formed with a pair of spaced integral right angular feet 2 which latter engage snugly against the bottom side of the lay. The web 1 is formed with a pair of holes in which attaching screws 3 are received and driven into the lay. The cen-

tral part of the web 1 is formed with a 50 preferably circular boss 5 which projects rearwardly and is formed with a threaded aperture to receive the bolt 6. A circular hole 7 is bored in the lay L to receive the boss, but the wall resultant from the boring 55 of the hole loosely receives the boss 5 so that such wall is not subjected to any rotative action of the boss as in the old expedient of the nut which has been held by the wall or walls against turning. 60

In use, the pick stick check, which may be of any type, for example that disclosed in our Patent No. 1,322,789 of Nov. 25, 1919, is mounted on the bolt 6 so as to be supported thereby. 65

Any tendency of the device to rock about the boss, due to the weight of the check at the outer end of the bolt 6, will cause the feet 2 to move upwardly and be braced against the bottom of the lay thereby. 70 Similarly the inner end of the boss 5 will be braced against the upper wall of hole 7.

Having thus described our invention, what we claim as new and desire to secure by Letters Patent is:—

1. In a loom check mounting, a bracket having a vertical front web formed to seat against an end of the loom lay and having a spaced pair of right-angular feet at the ends of its lower side to engage the bottom side of said lay, fastening screws extending through the web and into the lay, and a central boss integral with the web and having a threaded bolt-receiving opening therein, said boss being formed to be received in an 85 opening provided therefor in said lay.

2. In a loom check mounting, a bracket having parts formed to seat on and against two adjacent faces of a loom lay, means to secure the bracket to the lay, a boss having a 90 threaded aperture projecting outwardly from the bracket, and a bolt threaded into said aperture.

3. In a loom check mounting, a bracket having parts formed to seat on and against two adjacent faces of a lay of a loom, means to secure the bracket to the lay, a boss having 95 threaded aperture projecting outwardly

from the rear face of the bracket and receivable in an opening provided therefor in said lay, and a bolt threaded in said aperture.

4. In a loom check mounting, a bracket, means to attach the bracket to a loom lay, a boss having a threaded perforation carried by the bracket, and a bolt threaded into said perforation.

In testimony whereof we have signed our names to this specification in the presence 10 of two subscribing witnesses.

JAMES A. ANDREWS.
JOHN W. HERBERT.
